UNITED STATES PATENT OFFICE.

JOHN KAUFMAN, OF PRAIRIE DU SAC, WISCONSIN.

SPRING-HINGE.

1,344,538.

Specification of Letters Patent.

Patented June 22, 1920.

Application filed April 3, 1920. Serial No. 371,071.

To all whom it may concern:

Be it known that I, JOHN KAUFMAN, a citizen of the United States, residing at Prairie du Sac, in the county of Sauk and 5 State of Wisconsin, have invented new and useful Improvements in Spring-Hinges, of which the following is a specification.

The present invention has reference to a means for converting an ordinary hinge into 10 a spring hinge.

The improvement is in the nature of a door closer, and while primarily devised for employment on the hinges of automobile doors may be applied with equal efficiency 15 on other hinged devices, and the primary object is to produce a member constructed to provide crossed wings which are connected by spring wings whereby the said coils will exert a pressure toward each other, 20 the wings being arranged on the opposite sides of the butts or plates of an ordinary hinge, and the pintle for the barrels of the hinge, or a longer pintle may pass through the connecting ends of the wings and also 25 the barrels of the hinge.

A further object is to produce a door closing means designed to be employed as an attachment for a hinge, that shall be constructed from a single strand of spring 30 wire, so that the same may be cheaply manufactured, and one which will exert a desired pressure upon the outer faces of the hinged plates to force the same toward each other, and consequently maintain the door con- 35 nected by the hinge in a closed position.

The drawings illustrate a satisfactory embodiment of the improvement reduced to practice.

In the drawings:—

40 Figure 1 is a view illustrating the application of the improvement.

Fig. 2 is a top plan view thereof.

Fig. 3 is a view of the improvement de- tached.

45 In the drawings I have illustrated my improvement as applied to a hinge of an automobile door. The plates of the hinge are indicated by the numeral 1, the inter- engaging barrels by the numeral 2 and the 50 pintle that passes through the barrels by the numeral 3. In instances where the pintle 3 is only of a length to pass through the barrels of a hinge, said pintles are discarded when my improvement is attached, 55 as a comparatively long pintle is required

as will be apparent from the following de- scription.

My improved attachment for hinges is constructed from a single strand of spring wire and includes wings 4 and 5 respec- 60 tively. Each of the wings comprises a mem- ber which is U-shaped in plan, the inner wing 5 being of a less length than the outer wing 4, and the wings cross each other, that is the parallel arms of the U-shaped 65 wings are disposed at opposite angles. This angular relation of the wings is provided for by the spring connecting means for the arms of the said wings. The connecting means is provided by coiling the wire, as 70 indicated by the numeral 6. The coils are of a frusto-conical formation, being wider at the portions thereof connected to the arms of the inner wing 5 and gradually decreas- 75 ing in width to their connection with the arms of the outer wing 4. The distance be- 80 tween the coils 5 corresponds to the length of the hinge, and the said coils are disposed over the ends at the barrel portion of the hinge after the pintle 3 has been removed. 85 By this arrangement it will be noted that one of the wings, 5, will contact with one of the plates 1 of the hinge, and the second wing, 4, will contact with the outer face of the second plate 1. The removed pintle, or 90 a longer pintle, as heretofore stated is passed through the coils and through the barrels 2, so that the device is thus con- 95 nected to the hinge and the crossed wings, exerting a pressure toward each other will force the hinged plate into contacting en- gagement. Thus it will be seen that when the door is opened in the usual manner my improvement will cause the same to be 100 swung closed. The confronting ends of the wire that constitute the improvement ter- minate approximately centrally with the outer member of the wing 4, and these ends are received in a sleeve 7.

My improvement is of an extremely sim- 100 ple nature and in no way detracts from the ornamentalism of the hinge on which it is positioned.

Having thus described the invention, what I claim is:—

1. An attachment for hinges for swing- 105 ing the plates thereof against each other, comprising a member including crossed wings that are connected by spring coils which are disposed over the barrel of the 110

- hinge plate and secured thereto by the pintle connecting the plates whereby each wing will exert a spring pressure in the direction of the hinged plate with which it contacts.
- 5 2. In a means for converting an ordinary hinge into a spring hinge; a spring wire bent upon itself to provide two substantially U-shaped wings that are arranged in crossed relation to each other whereby to contact
10 with the outer faces of the respective plates

of a hinge, said wings having also parallel arms connected by coiling wire from the end of the inner to the end of the outer members, and the pintle connecting the plates to the hinge passing through the said coiled 15 portions of the wings for securing the same upon the hinge.

In testimony whereof I affix my signature.

JOHN KAUFMAN.
